BABY COMFORT CAB

Willard R. Tolen, Riverside, Calif.

Application November 16, 1944, Serial No. 563,726

5 Claims. (Cl. 5—284)

My present invention, in its broad aspect, has to do with improvements in air-cooling and conditioning means, and heating means for infant's cabs, cribs and mattresses. It is common knowledge that overheating of a baby is the occasion for much discomfort and illness, especially since a very young child spends so much of the time in a cab, crib or bed, or upon a mattress. An uncomfortable and overheated baby is not only an annoyance to the mother, but the occasion of endless labor. The same may be said of a baby who is not warm enough. My present invention is designed to provide an air-cooling and conditioning means, which may be regulated and adjusted, and which will not induce drafts, and which may be turned on and off at will. I also provide means for heating the mattress to prevent the baby from becoming chilled or cold in cold weather. While my device is especially designed for a cab, it may be used with a crib, bed or the like.

Other and equally important objects and advantages of my invention are—(1) to provide a device which may be easily regulated and adjusted; (2) to provide means for properly distributing the cooling effect without drafts; (3) to provide a novel, useful and practical mattress construction; and (4) to provide a useful and practical heating device.

Still further objects and advantages will be apparent from the following description and drawings, but it is to be understood that changes in form, material, size, shape, construction and arrangement of parts may be made without departing from my broad inventive concept or the scope of the appended claims.

In the drawings wherein I have illustrated a preferred form of my invention—

Figure 1 is a top plan view partly broken away to show interior parts;

Figure 2 is a sectional side elevation through the cab, partly broken away;

Figure 3 is a transverse section on the line 3—3 of Figure 1;

Figure 4 is a transverse section on the line 4—4 of Figure 1, and

Figure 5 is a plan view of the bottom supporting frame.

In the drawings wherein like characters of reference are used to designate like or similar parts throughout the several views—

The numeral 1 designates a part of a baby cab of suitable construction and which has sides 2, a front 3, a back 4 and a bottom 5 which is inclined downwardly from the sides and front and back

toward the center where the same has a circular flanged opening 6 covered with wire screening 7. Mounted in the opening between the flanged part 6 is a motor 8. The motor support is designated 9 and a battery 10 is mounted on the floor in the circuit 11 with the motor and a push button switch 12 at the back of the cab. The motor drives a fan 13.

A mattress 14 having a bottom 15, ends 16, sides 17, and a top 18 is supported in the cab, and has at its bottom a strong wire frame 19 and longitudinal supporting members 20 and transverse supporting members 21. The transverse supporting members are in spaced pairs on which are seated telescoping hollow tubes 22 which are oval in cross-section and which extend upwardly to the top of the mattress and have flanges 23 and 24 and their upper and lower edges respectively. About each tube is a spring 25 which presses against the flanges. The tubes are arranged in spaced pairs adjacent the sides and ends, thus providing a part of the mattress medially and longitudinally and medially and transversely in which is a hollow rubber tubing member 26 in the nature of a cross with side legs 27 and longitudinal legs 28—the center being over the fan 13 as shown in Figure 1. The tubing member is designed to be filled with hot water or warm water through a capped filler mouth 29. A suitable filler of cotton or the like 30 extends about the tubes 22 and rubber tubing member 26 and beneath the supporting members 20 and 21. The edges of the mattress are rolled over and outwardly to form extensions as at 31—see Figures 3 and 4—to prevent rising drafts about the edges of the mattress, and beneath these extensions are openings covered by superposed vented plates 32 to regulate passage of air through and in the mattress, since by sliding the outer plate 33 with reference to the inner plate 34 the size of the openings 35 may be regulated. The outer plate is slidably held in a flanged frame 36 and has handles 37. A screen 38 is provided back of the plates as shown in Figure 3. By these means, air is forced upwardly through and into the mattress by turning on the fan 13, or the mattress is warmed by filling the member 26 with cold, or warm or hot water, and the baby is at all times kept comfortable.

From the foregoing, it is believed that the operation and advantages of my invention will be apparent, but it is again emphasized that interpretation of the scope thereof should only be conclusive when made in the light of the subjoined claims.

I claim:

1. An air conditioning and cooling device for baby cabs and the like, comprising a fan, a mattress having overhanging extended edge portions, adjustable ventilating means on the mattress below the extended edge portions, telescoping tubular members in the mattress providing air-circulating channels, springs to hold said members extended, and a fluid containing member in the mattress.

2. The invention as defined in claim 1 wherein the cab has a downwardly inclined bottom with the fan located at the lowermost point, means for cutting the fan on and off, and the fan located below the mattress.

3. The invention as defined in claim 1, wherein there are multiple tubular members arranged in pairs, and wherein the fluid containing member

is in the form of a cross with the spaced pairs arranged between the arms thereof.

4. The invention as defined in claim 1 wherein the fluid containing member is oval in cross section and formed substantially like a cross with lateral and longitudinal arms, and has a capped filler opening.

5. An air conditioning and cooling and heating device for babies comprising a mattress having a supporting frame carrying inner springs, tubular members formed with telescoping sections within the springs and forming channels for air circulation, a tubular member between said sectional tubular channels to receive hot or cold fluid, an air circulating means, the mattress having overhanging lateral edges, and adjustable valve means below the edges to control ventilation within the mattress.

WILLARD R. TOLEN.
